(57) **CLAIM**

The ornamental design for a wheel rim for vehicles as shown and described.

DESCRIPTION

FIG. 1 is a front perspective view of the wheel rim for vehicles showing my design;

FIG. 2 is a front elevation view thereof;

FIG. 3 is a left-side elevation view thereof;

FIG. 4 is a rear elevation view thereof;

FIG. 5 is a right-side elevation view thereof;

FIG. 6 is a top plan view thereof; and,

FIG. 7 is a bottom plan view thereof.

Portions of the wheel rim for vehicles shown in broken lines form no part of the claimed design.
